UNITED STATES PATENT OFFICE.

CARL RUSK, OF ASTORIA, OREGON.

HAULING-IN DEVICE.

Application filed May 4, 1925. Serial No. 27,803.

The object of my invention is to provide a drum-like hauling-in device for trolling lines, and the like, said device being provided with a plurality of automatic gripping devices 5 spaced closely about its periphery, each, of which, is independently adapted at a predetermined position to grip the line, to draw the same along with the rotation of said device, and to release the same. The use of my improved mechanism permits the line to be drawn in in substantially a horizontal plane and to be drawn by each automatic gripping device for approximately one-fourth of the revolution of said device and to be released at 10 a point where the line extends pendent from said drum. The line can thus be coiled on the deck of the boat instead of being wound about the circumference of the drum.

Trolling lines and the like carry a number 20 of hooks or similar devices spaced along said line and thus the hauling-in devices must be arranged to grip the trolling line away from said points of connection. A further object of my invention therefore is to provide adjustable means by which the position of the gripping action, relative to the rotation of the drum, can be adjusted so as to permit the operator thereof to vary the position at which the gripping devices act without interrupting 25 the rotation of said devices.

A further and more specific object of my invention is to arrange the parts of my hauling-in device so that the gripping mechanism is entirely enclosed within the drum. To attain 35 this object I make the drum in two separable halves and provide a projection on one of said halves of such length as to space said halves so as to define a groove between them in which the trolling line will be received. The gripping devices are mounted in recesses 40 in said drum halves and arranged alongside of said grooves so as to hold the same against one of said drum halves but not being required to support any of the load thereon.

45 A further object of my present invention is to provide yielding devices between said drum halves so that if an auxiliary device or the connections therefor should become gripped by said gripping devices, said drum halves would be permitted to spread slightly so as to prevent injury to the gripping devices, because of the increasing thickness of the trolling line at this point.

The details of construction and mode of operation of my invention are hereinafter de-

scribed with reference to the accompanying drawings, in which:

Fig. 1 is a perspective view of the stern end of a boat with my hauling-in device mounted thereon;

Fig. 2 is a side elevation of said hauling-in device;

Fig. 3 is an edge elevation of said device, taken in direction of the arrow 3 in Fig. 2;

Fig. 4 is a side elevation of said device in 65 the direction of the arrow 4 in Fig. 3;

Fig. 5 is a plan view of said device carried upon the stern end of said boat;

Fig. 6 is a section through said device taken 70 on the line 6—6 of Fig. 3;

Fig. 7 is a similar section taken on the line 7—7 of Fig. 3;

Fig. 8 is a section through said device taken on the line 8—8 of Fig. 2;

Fig. 9 is a section taken on the line 9—9 75 of Fig. 2;

Fig. 10 is a perspective detail of the cam which controls the gripping devices of my device; and

Fig. 11 is a fragmentary perspective view 80 of the two drum halves spread apart and with the gripping devices removed therefrom.

My invention comprises a drum *a* made up of two drum halves *a*¹ and *a*². Said halves 85 are held together by bolts *b* and are rotatably mounted upon a horizontal shaft *c*. Said shaft is carried between two spaced standards *c*¹ and *c*², fastened to the deck *d*¹ of the boat *d*. Fastened to the hub *a*³ of said drum 90 half *a*² are two integral gears *a*⁴ and *a*⁵ of different diameters. A shaft *e* is arranged parallel to said shaft *c* and is carried by bearings formed in the member *f* and in the standard *c*². Said shaft *e* carries gears *g*¹ and 95 *g*² of different diameters fixed thereto and a gear shifting lever *h* is arranged to throw either of said gears *g*¹ and *g*² into meshing position with the gear *a*⁴ or the gear *a*⁵, respectively.

100 Said shaft *e* is driven by a beveled gear *i*, which meshes with the beveled gear *j* upon the driving shaft *j*¹. Said shaft *j*¹ is journaled in bearings *j*² upon the deck *d*¹ of the boat *d*. Said shaft *j*¹ preferably extends 105 through said deck so that it can be connected to the propelling engine for said boat.

The drum half *a*² is provided with a plurality of radial recesses *a*⁶ and with two concentric recesses *a*⁷ and *a*⁸. The recess *a*⁷ is 110

relatively small in diameter and lies within the recess a^8 . The drum half a' is provided with a shouldered portion a^9 which extends from the face of said drum half again farther than the depth of the recess a^8 . Said shouldered portion seats in the recess a^8 and thus, because of the greater length thereof, the halves are spaced apart so as to provide a groove a^{10} between said halves and about said shouldered portion. The drum half a' is provided with a recess a^{11} which corresponds in size to the recess a^7 and opposes the latter and thus the operating cam k , fixed to the shaft c , can be housed equally in said two recesses.

A coil spring l also housed within the drum half a' bears against the cam k and holds the same tightly against the face of the drum half a^2 . An irregular guideway k' is cut upon the periphery of the cylindrical cam k . A plurality of clamping levers m are pivotally carried between the drum halves a' and a^2 being in part carried in the radially disposed recesses a^6 and part carried by corresponding recesses in the drum a' .

The line n to be gripped is guided into the groove a^{10} formed between the drum halves, by the outwardly flared, concentrically arranged guiding flanges a^{12} and a^{13} upon said drum halves, respectively. In said groove, it is gripped in one position by the clamping levers m . In said position it is to be noted that the lip a^{14} on said drum half a^2 completely overhangs the ends of said clamping levers so as to prevent the cable being held up on said ends instead of falling into the groove a^{10} ; said ends of the clamping levers also are as thick as the width of the groove a^{10} so that said cable cannot become wedged, inadvertently, behind the lever when it is in operative position.

Said clamping levers are fulcrumed upon pins m' and are mounted with one end bearing in the irregular peripheral groove k' on the cylinder-cam k . The irregularities of said groove cause said clamping levers to be moved into and out of engaging position relatively to said line n . The groove k' is preferably arranged so as to move said clamping levers into gripping position for only approximately one-fourth of the revolution of the drum. As shown in Fig. 6, if the trolling line is being hauled in in substantially a horizontal plane, the control devices are arranged so that the clamping levers m in the upper rear quarter of said wheel are moved into the operative position. The trolling line thus will be gripped as it passes over the top of said wheel in a horizontal plane and will be released as it passes from off said wheel in a vertical plane.

I provide means for adjusting said cylindrical cam k relative to said drum by providing a lever o provided with locking pawl mechanism o' which is adapted to engage

the toothed sector p fastened to said standard c' . By moving said operating lever o from the position shown in full line in Fig. 4 to the position shown in dotted lines in said figure, the position of the clamping action of said clamping levers will be correspondingly changed.

The trolling line to be hauled in is placed over the drum and it will be guided into the slot a^{10} by the converging, flaring, circumferential flanges a^{12} and a^{13} , respectively. The operating lever o is set so that it will grip the line in a predetermined sector. For example, if the line n is being drawn in, in substantially a horizontal line, the gripping devices are arranged so that they will grip the line in the manner shown in Fig. 6, and the drawn-in portion of said line will be coiled behind the hauling-in device upon the deck d' in such a manner that it can be conveniently paid out later. Or in case the line is to be passed over one of the other quadrants of the drum, the lever o is operated to rotate the cam k so that the clamping levers will clamp and release the cable in the selected quadrant.

The gears g' or g^2 are meshed with the gears a^4 or a^5 , respectively, and the drum is rotated in a clockwise direction, as shown in Figs. 1, 2 and 6, which tends to draw in the line n .

Also when a connection n' holding the leader n^2 for a fish-hook n^3 reaches the point where it will be gripped by one of the levers m the operator adjusts said lever o so that the gripping levers will not clamp the thicker connection n' . This adjustment is made by disengaging the locking pawl mechanism o' from the tooth sector p and the lever is moved angularly, as viewed in Fig. 4, to the desired position. It is then either returned to its original position or locked in said position. If, inadvertently, one of said operating levers m would strike upon one of the thicker connections n' , the clamping lever m will not be broken thereby because the coil spring l will yield slightly to permit the cam for the clamping levers, to slide along the shaft c to accommodate this increasing thickness.

I claim:

1. In an apparatus of the character described, a shaft, a driven cable-drum rotatably mounted on said shaft, said drum consisting of two sides respectively provided with cable retaining flanges spaced to provide a cable receiving circumferential slot between them, said sides formed to provide an interior central chamber between them, a series of radially disposed clamping levers completely housed within said drum, a cam fast on said shaft within said central chamber with which cam said clamping levers are operatively connected, the interior faces of said sides being provided with means for supporting the cable portion entering said slot

in position for being clamped by said clamping levers, and a lever fast on said shaft exterior of the drum, whereby partially to rotate said cam and thus set the action of the 5 clamping levers relatively to a selected circumferential portion of the drum.

2. In a device of the character described, a shaft, a driven cable-drum rotatably mounted on said shaft, said drum provided 10 with a circumferential cable receiving slot, one side of said slot constituting a clamping surface, a series of radially disposed clamping levers pivotally mounted in said drum and arranged to clamp the cable against 15 said clamping surface, a cam carried by said shaft within said drum, said cam provided with portions adapted to engage the clamping levers thereby to bring the latter successively into action during the rotation of the 20 cable-drum.

3. In an apparatus of the character described, a shaft, a driven cable-drum rotatably mounted on said shaft, said drum being provided with circumferential cable retaining flanges and with a central chamber between its sides, automatic cable clamping devices completely housed in said drum, adapted to clamp and release again, successively, during the rotation of said drum, said devices consisting of a plurality of radially 25 disposed clamping levers and a cam fast on said shaft within said drum with which said clamping-levers are operatively connected, and means operable from the exterior of said drum to give said cam a partial rotation, 30 thereby to set the action of said clamping devices relatively to a selected circumferential portion of the drum. 35

CARL RUSK.
